UNITED STATES PATENT OFFICE.

CHARLES STALEY, OF STERLING, ILLINOIS.

TOE-WEIGHT.

SPECIFICATION forming part of Letters Patent No. 694,586, dated March 4, 1902.

Application filed September 14, 1901. Serial No. 75,399. (No model.)

To all whom it may concern:

Be it known that I, CHARLES STALEY, a citizen of the United States, residing at Sterling, in the county of Whiteside and State of Illinois, have invented certain new and useful Improvements in Toe-Weights, of which the following is a specification.

My invention relates to improvements in toe-weights; and the object of my invention is the provision of a toe-weight which can be easily applied or removed and which cannot work loose or become detached and which will be of simple, inexpensive, and practical construction.

15 To attain the desired ends, my invention consists of a toe-weight embodying novel features of construction and combination of parts, substantially as disclosed herein.

Figure 1 represents a perspective view of 20 my toe-weight applied. Fig. 2 represents a central sectional view. Fig. 3 represents a detail view of the parts detached. Fig. 4 represents face views of modified forms of spur or base plates.

25 In the drawings, A designates the hoof of the horse, to which is rigidly secured the spur or base plate B, which is of angular or three-cornered form, the upper end C being raised and formed with a socket or recess D, with 30 which communicates the T-shaped slot E. Fitting in the recess is the flat head F, formed with the threaded stem or shank G, said stem being provided with the squared portion or shoulder G', which fits snugly in the slot and 35 prevents turning of said stem, and the round threaded portion passes through the opening H in the toe-weight proper, J, and is engaged by the nut K, which firmly holds the weight upon the spur or base plate, the weight being 40 cast or formed with a cavity L to snugly fit

upon the base-plate and make a neat joint and secure the parts firmly together. In the modified forms of my invention the slot is arranged differently, but the function is performed in the same manner.

45

The weight proper, it will be seen, has the seat or cavity or recess L of triangular shape, with one portion of said recess deeper than the rest, which causes the weight to fit snugly and perfectly over the plate and make a neat joint and a secure fastening of the weight upon the plate.

50 It will be seen that my toe-weight can be applied and removed with ease, that it cannot work loose, that it is compact and neat in appearance, and that it is durable, inexpensive, and practical.

I claim—

55 The toe-weight herein shown and described, consisting of the weight proper having the substantially triangular seat or recess one portion thereof being deeper than the other portion, a substantially triangular base-plate adapted to be secured to the hoof and fitting snugly in the recess of the weight, a raised portion formed on the base-plate providing a cavity or recess with a T-shaped seat communicating with the said recess, said raised portion of the base-plate fitting the deep portion of the seat in the weight, and a square 60 flat head fitting in the recess of the base-plate, a stem passing from the head through the weight, and a securing-nut on said stem.

65 70 In testimony whereof I affix my signature in presence of two witnesses.

CHARLES STALEY.
